(57) **CLAIM**

The ornamental design for a medical lighting device, as shown and described.

DESCRIPTION

1. Medical lighting device

1.1 : Perspective

1.2 : Front

1.3 : Back

1.4 : Left

1.5 : Right

1.6 : Top

1.7 : Bottom

The dashed broken lines in the drawings show portions of the medical lighting device that form no part of the claimed design.

1 Claim, 7 Drawing Sheets
